EMIL C. HANSEN, OF MEDIA, PENNSYLVANIA, ASSIGNOR OF ONE-HALF TO ROBERT FUSSELL, OF MEDIA, PENNSYLVANIA

NAUTICAL TOY

Application filed April 16, 1931. Serial No. 530,459.

The present invention relates to toys and more particularly to a nautical toy for controlling boat or ship movements.

Some of the objects of the present invention are to provide a novel, entertaining and instructive toy employing the use of boats; to provide a nautical toy wherein boats are caused to travel without visible means of propulsion; to provide a nautical toy wherein actual navigating conditions can be reproduced in miniature; to provide a device which functions as an educational means to instruct in the use of a compass and the control of a vessel so that the latter follows a definite course; to provide a docking means for miniature vessels; to provide an electrically operated and controlled toy utilizing a tank of water and boats thereon; and to provide other improvements as will hereinafter appear.

In the accompanying drawings, Fig. 1 represents a plan of a nautical toy embodying one form of the present invention; Fig. 2 represents a plan in part section with the water trough removed; Fig. 3 represents a section on line 3—3 of Fig. 1; Fig. 4 represents an end elevation from the control box end of the device; Fig. 5 represents a section on line 5—5 of Fig. 2; Fig. 6 represents a diagram of the electric circuits and associated parts; and Fig. 7 represents a detail of the compass needle control mechanism.

Referring to the drawings one form of the present invention consists of a receptacle 10 having a bottom 11 and sides 12, the latter rising well above the bottom 11 in order to receive a trough 13 in which the water for floating the toy boats 14 is contained. As here shown the trough 13 has marginal flanges 15 which seat upon the top of the sides 12 and thus support the trough in suspended operative position while allowing it to be lifted out whenever necessary. The depth of the trough 13 while sufficient to hold an amount of water for flotation purposes is such as to provide a chamber 16 above the bottom 11 of the receptacle 10. While the receptacle 10 is illustrated as of rectangular shape it is to be understood that this is not a limitation of the invention, as in some instances other

shapes may be found more desirable in order to simulate actual nautical courses.

For the purpose of imparting motion to the boats 14 each has a hull either of soft iron or of some other substance with an attached metal part designed to act as the armature of a magnet, the essential thing being that the boat is caused to be drawn toward a magnetic field produced for the purpose of moving the boat in a certain direction. To this end therefore a plurality of magnet coils 17 are mounted upon the bottom 11 within the chamber 16 and in such close proximity to the bottom of the trough 13 as to insure the magnetic field or flux from any energized coil 17 permeates the water in the tank 13 in a restricted area so that any boat within the range of the field will be caused to move toward the attracting area. The tank 13 is of zinc though it may be of any material which does not act to obstruct the magnetic lines of force. The arrangement of the coils 17 may be haphazard but preferably they are given a very definite and related position, one being below each docking place of a boat and the others arranged so that a predetermined course laid out with respect to compass points is provided.

In order to energize the coils 17 each has one of its ends connected by a conductor 18 to a common return which in this instance is a metallic lining 20 serving as a ground and to which the respective coil ends are conductively attached. A conductor 21 leads from the ground lining 20 to one terminal 22 of the secondary of a step-down transformer 23. The other end of each coil 17 is connected by a conductor 19 to a selecting device which in this instance consists of a commutator type of switch having as many terminal contacts 24 as there are magnet coils 17 and to each of which one of the conductors 19 is connected. A contactor in the form of a rotatable switch arm 25 is arranged to be moved from one contact 24 to another in order to make selection of the particular circuit desired. The arm 25 is connected by a conductor 26 with a switch arm 27 of a rheostat 28 which in turn is connected to the terminal 30 of the transformer 23, the

said terminal 30 being one end of the transformer secondary of which the terminal 22 is the other end.

As a means for rotating the commutator switch arm 25 it is fast to a spindle 31 which is here vertically mounted and is journalled at its lower end in a support partition 32 and at its upper end in a bracket 33 fixed to the inside of the top 34 of a box 35. Fast to the spindle 31 is a bevel gear 36 in mesh with a like gear 37 fast to a shaft 38 journalled in an extension of the bracket 33 and carrying a control wheel 40 on its end and in a position for convenient manipulation.

For indicating the course a boat is to take with relation to the points of the compass the top 34 of the box 35 mounts a compass 41 having the usual encircling direction abbreviations so that the box 35 with its associated parts can be positioned for use with the "north" properly oriented. In this construction the compass needle 42 is arranged to follow the rotation of the control spindle 31 by providing a magnetized arm 43 which is fast to the spindle 31 and extends radially therefrom to swing in a plane parallel to the plane of the needle 42 and in such close proximity thereto as to subject the needle to the flux emanations. Hence as the spindle 31 is turned the magnetized arm 43 follows its movement and thus causes the needle 42 to swing in a corresponding manner. It follows therefore by selecting a point of the compass, for example NE., and turning the control wheel 40, that the needle 42 can be swung to NE. position and when it reaches that position the contactor 25 will engage the contact 24 to close the circuit of the magnet coil 17 which corresponds to that position and the result is the boat will be drawn in a NE. direction.

At suitable locations docks 44 are fixed to the sides 12 and provide one or more slips 45 into which the boat or boats can be guided, it being understood that one of the magnet coils 17 is located near the entrance to each slip 45. When a boat is in one of the slips 45 it is desirable that it be held against working its way out due to movement of the water or for other reasons and to that end a drag or brake plate 46 is pivoted to the dock frame on a horizontal pivot 47 so located as to contact with the bottom of a boat in the slip in one position, and in its non-holding position to be out of contact therewith. A counter weight 48 is carried by the dock end of the plate and the arrangement is such that when the plate 46 is free to move the weight 48 will swing it up to boat engaging position where the pressure is sufficient to hold the boat in the slip 45. The plate 46 is of material or carries material to act as an armature and move in response to magnetic flux and therefore when the control coil at the entrance to a slip is energized the plate

46 will be pulled down counter to the action of the weight 48 and so held until the boat is out in the water and the coil deenergized.

In order to fully approximate actual ship starting, stopping and control conditions a manually operable bell 50 is mounted in the control box 35 to simulate engine room signals on the boats. Also a buzzer 51 or the like can be connected into the circuit and controlled by a hand switch 52 so as to reproduce whistle signals.

Since it is desirable to have the device simulate actual operating conditions and present nautical problems such as met in the navigation of rivers and other bodies of water the arrangement of the course directing magnets 17 is different for different locations. Naturally the arrangement of magnets for all devices representing the same course are the same. In the arrangement illustrated the magnets are located to simulate on a small scale the course of vessels leaving a dock in Chester, Pennsylvania, proceeding to Philadelphia, and docking at the latter port. That this course can be accurately charted by the user of the device, a course chart 53 is attached to the top of the control box 35 or other convenient visible location and has printed thereon the required course data so that by successively setting the compass needle 42 in accordance with the charted direction, the magnet coils 17 will be correspondingly energized to cause the boat to proceed upon the designated course. The advanced operator can if desired ignore the furnished directions and work directly from a chart of that locality as supplied to all navigators.

While only a single form is shown in which this invention may be embodied, it is to be understood that the invention is not limited to any specific construction, but might be applied to various forms without departing from the spirit of the invention or the scope of the appended claims.

Having thus described my invention, I claim:

1. A nautical toy comprising a trough for holding water, a boat floatable on said water and responsive to a magnetic flux, a plurality of electro-magnets located below said trough, a compass, a source of electrical energy, and means including a switch to selectively energize said magnets and to cause said compass to indicate the course defined from one selected magnet to another.

2. A nautical toy comprising a trough for holding water, a boat floatable on said water and responsive to a magnetic flux, a plurality of electro-magnets located to create a magnetic flux, when energized, to influence said boat, a compass, means including a device for selectively energizing said magnets, a source of electrical energy, and means for synchronizing the movement of the needle

of said compass with said device whereby the course of said boat is indicated from one selected magnet to another magnet.

3. A nautical toy comprising a trough for holding water, a boat floatable on said water and responsive to a magnetic flux, a plurality of electro-magnets located to create a magnetic flux when energized to influence said boat, a source of electrical energy, means for selectively energizing said magnets, and a compass having a needle responsive to said selecting means.

4. A nautical toy comprising a trough for holding water, a boat floatable on said water and responsive to a magnetic flux, a plurality of electro-magnets located to create a magnetic flux when energized to influence said boat, a source of electrical energy, a plurality of circuits for the respective magnets, a switch for selectively closing said circuits, a compass, and means responsive to the movement of said switch for actuating said compass.

5. A nautical toy comprising a trough for holding water, a boat floatable on said water and responsive to a magnetic flux, a plurality of electro-magnets located to create a magnetic flux when energized to influence said boat, a source of electrical energy, a plurality of circuits for the respective magnets, switch means including a rotatable axis for selectively closing said circuits, a compass, and a magnet carried by said axis and located to cause the needle of said compass to follow the movement of said switch.

6. A nautical toy comprising a trough for holding water, a boat floatable on said water, a dock for said boat, a pivoted holding member submerged in said dock, a weight normally pressing said member against said boat to hold said boat in said dock, and an electro-magnet arranged when energized to release said member from said boat.

7. A nautical toy comprising a trough for holding water, a boat floatable on said water and responsive to a magnetic flux, a plurality of electro-magnets located to create a magnetic flux when energized to influence said boat, a source of electric energy, means for selectively energizing said magnets and an indicator responsive to said selective means.

Signed at Media, county of Delaware, State of Pennsylvania, this 8th day of April, 1931.

EMIL C. HANSEN.
